UNITED STATES PATENT OFFICE.

JOHN A. SERRELL, OF NORTH PLAINFIELD, AND JAMES LOGAN FITTS, OF PENSAUKEN TOWNSHIP, CAMDEN COUNTY, NEW JERSEY; SAID FITTS ASSIGNOR OF HIS RIGHT TO WARREN WEBSTER & CO., A CORPORATION OF NEW JERSEY.

STEAM-HEATING APPARATUS.

1,312,275.

Specification of Letters Patent.

Patented Aug. 5, 1919.

Application filed January 7, 1916. Serial No. 70,706.

To all whom it may concern:

Be it known that we, JOHN A. SERRELL, a citizen of the United States, and resident of North Plainfield, county of Somerset, and 5 State of New Jersey, and JAMES LOGAN FITTS, a citizen of the United States, and resident of Pensauken township, county of Camden, and State of New Jersey, have invented an Improvement in Steam-Heating 10 Apparatus, of which the following is a specification.

Our invention has for its object the provision of a radiator or heating coils with means for thermostatically controlling the 15 supply of steam thereto to maintain a substantially constant or uniform temperature in the room, kiln, drying oven, or other space or apparatus for which the invention is to be utilized; but in all cases the thermostat controlling the steam delivered to the radiator or coils is to be arranged close to the lower portion of said radiator or coils and above the floor, so as to be directly affected by the temperature conditions of the 20 cooler air circulating immediately adjacent to or under the lower portion of the radiator or coils and relatively close to the floor.

We have determined that the air flowing from various portions of a room or compartment toward and about the under portion of a radiator or coils, arranged close to the floor in the usual way, bears a certain temperature relation to the average room temperature, and we have utilized this cooler 30 air as the direct medium to affect a thermostat to control the admission of steam to the radiator or coils. The cooler air thus utilized is more nearly an average of temperature conditions in the room or chamber 35 than the air higher up and at any specific location considerably distant from the radiator or coils to be regulated; and moreover, the air being of a relatively lower temperature, the effect of its varying temperature 40 conditions upon a thermostatic device is more reliable and makes the thermostat more quickly responsive to said varying temperature conditions of said cooler air than if placed higher up where the temperature conditions are warmer.

With the above and other objects in view, the nature of which will be more fully understood from the description hereinafter, our invention consists in the provision of a 45 thermostatically operated member adjacent

to the lower portion of the radiator or coils and above the floor and utilizing the same for operating a suitable valve device for controlling the steam supply to the said radiator or coils, whereby its temperature is 50 automatically varied inversely with variations of the air passing to its lower portion to be heated for circulation; and further consists in certain features which enter into an organization of our improved apparatus; 55 all of which is hereinafter more fully described and defined in the claims.

Referring to the drawings:—

Figure 1 is a side elevation of a radiator having our improved thermostatic controlling devices applied thereto; Fig. 2 is a longitudinal sectional elevation of the thermostatically controlled valve shown in Fig. 1, with a portion of one of the chambers broken away; Fig. 3 is a sectional elevation 75 of a portion of Fig. 2 showing the adaptation of a handle for operating the manually controlled valve; and Fig. 4 is a side elevation with part of the valve in section illustrating a modification of our invention. 80

2 represents a radiator of any suitable construction, the same being illustrated of the conventional form consisting of a plurality of sections held together and supported above the floor by suitable legs 2^a so as 85 to provide a shallow space under the radiator and above the floor into which the cooler air from the room is caused to circulate, and by becoming heated, rises above the radiator. Steam is supplied to the radiator by means 90 of the supply pipe 3 and branch pipe 4, the said steam being preferably delivered to the upper part of the radiator. The steam thus supplied to the radiator is controlled by a valve 5 of any suitable construction, though 95 we have illustrated a special construction of valves which we prefer for use in connection with our improvements. 7 represents the return pipe for water of condensation and air from the radiator, and the connection of this 100 pipe 7 may be made through any of the usual return valves such as the thermostatically operated valve 8 which permits the passage of water and air but restricts the passage of steam, such type of valve being well known 105 and in general use. By employing suitable means on the return side of the radiator to restrict the escape of steam, it is manifest that the temperature conditions of the radiator may be varied by supplying more or less 110

steam through the pipes 3 and 4 under the control of the valve 5, and it is to accomplish this automatically, in accordance with the requirements due to varying temperature 5 conditions in the room being heated, that our improvements are directed. As will be understood by reference to Fig. 1, the valve 5 is shown as connected to the thermostatic motor 6 which preferably extends horizontally 10 from the valve 5 under the radiator and in the direction of its greatest length, the said thermostatic motor being located in the space 26 immediately beneath the radiator and above the floor so as to be acted upon by 15 the cooler air returning from all parts of the room and delivered to the radiator at its lower part.

We will now describe the details of our improved thermostatically controlled valve 20 by specific reference to Fig. 2. The body of the valve 5 is provided with a thoroughfare 9, 9, containing a valve seat 10 preferably formed as a bushing screwed into a transverse diaphragm which divides the 25 thoroughfare into two parts, and said bushing providing at opposite faces the valve seats, one of which may coöperate with a static or manually operated valve piece 22, and the other with an automatic or thermostatically operated valve piece 11. The 30 body is furthermore preferably provided with a union nipple 5^a for connection with the steam supply main 3, and also with a union nipple 5^b for connection with the 35 branch pipe 4 which connects with the radiator, though we do not limit ourselves to these minor details. The body is further provided with an opening in alignment with the valve seat bushing and into which is 40 screwed a bonnet 5^c through which a valve operating stem 12 slides, a steam tight joint being provided by the stuffing-box 13. As shown, the valve piece 11 is connected upon the end of the valve stem 12 so as to have 45 capacity for adjustment whereby it may properly seat upon the valve seat without creating any binding effect upon its guides. While we do not limit ourselves to any particular manner of attaching the valve piece 50 to the valve stem, the means shown is excellently adapted to the purpose and consists of a washer 11^a with spherical-shaped surfaces and clamped between the valve piece 11 and a bushing 11^b having a tapered 55 aperture, said bushing screwed into the valve piece at the rear. By this construction, the valve piece is positively moved with the stem but will adjust itself to the valve seat. The other end of the stem 12 is 60 adjustably screwed into the head 20 of the expansible bellows structure 18 which may be made in any suitable manner and providing an interior chamber which contains an expansible fluid or preferably with associated 65 gas, adapted to be expanded under

the variations in outside temperature. The expansible sections are connected by tubular sections 19 which are shown in Fig. 2 as loosely abutting, as when the expansible sections are fully collapsed and the valve 70 wide open. The other end of the expansible member is brazed or otherwise secured at 21 into the end of a long tubular vessel portion 14 which also contains expansible fluid of any suitable character, preferably with 75 associated gas, which will expand by variations in temperature of the surrounding atmosphere. Any change of the volume of the said expansible medium within the common chamber of the parts 14 and 18 will 80 operate upon the expansible bellows or motor portion 18 to assist in the expansion thereof for moving the valve piece 11 to more or less close the passage of steam through the thoroughfare of the valve. We do not in 85 any manner restrict ourselves to the special construction of the expansible member, as this may be made in any manner desired, and the particular construction illustrated is by way of example only. As it is necessary 90 for proper operation of the thermostatic motor, in its operation of shifting the valve piece, that the non-active end 21 thereof shall be held in a fixed relation with respect to the valve body, this is accomplished by 95 means of the inclosing tubular part 16 which is screwed upon the bonnet 5^c of the valve body and adjustably screwed into an annular flanged portion 15 extending from the thermostatic chamber member portion 100 14, and by which the motor may be adjusted relatively to the valve body in the direction of the valve stem. The thermostatic motor portion, together with the thermostatic chamber portion 14, may be rotated so as to be screwed upon the tubular part 16 to a greater or less extent to provide the proper adjustment of the valve piece 11 relatively to the seat on the bushing 10, and when so adjusted, the parts may be 110 locked by means of the threaded sleeve 17 acting as a lock-nut. The adjustment is required to provide proper coöperation between the parts to maintain a regulation of the steam supply which will insure a main- 115 tenance of temperature predetermined upon. This will be understood by recognizing that when the air of the room exceeds the maximum temperature permissible, the temperature of the air below or adjacent to the lower 120 portion of the radiator and acting upon the thermostatic devices of the steam controlled valve may cause the valve piece 11 to close tightly upon its seat, and to insure this the parts must be adjusted as above stated. For 125 any temperature of the room less than the maximum temperature, the thermostatic motor will be expanded to a correspondingly greater or less extent and thereby correspondingly adjust the valve piece 11 to 130

vary the admission of steam to suit the requirements of the radiator in maintaining the proper predetermined temperature of the room required. Any other suitable manner of adjusting the parts may be employed, such for example by loosening the lock-nut 20^a on the stem 12 and adjusting the stem in the head 20 of the thermostatic motor, and we therefore do not limit ourselves to any particular manner of adjusting the thermostatic valve devices. As will be seen from Fig. 1, the closed thermostatic chamber 14 is preferably quite long relatively to the bellows or motor portion, and this is to enable the expansible medium as a whole to be affected throughout substantially the whole length of the radiator. It will therefore be understood that the length of the chambered portion 14 will be increased or decreased to suit the variations in the length of the radiator itself or as occasion may suggest or require. We do not restrict ourselves in any manner to the particular construction of this elongated chamber portion 14, but have shown a convenient construction in which a piece of tubing is tightly brazed or otherwise secured to the non-active tubular end 21 of the motor device so that these parts provide, in effect, one chamber.

In addition to the thermostatically operated valve piece 11, we prefer to employ the manually controlled valve piece 22, which is screwed through the body and adapted to seat upon the inlet side of the bushing 10, and this valve piece or plug may be provided with a socket 23 into which a key 27 may be inserted for rotating it, as indicated in Fig. 3. By removing the key, the plug is not easily manipulated and therefore its operation may be restricted to certain attendants whose duty it is to operate the said static valve piece either for the purpose of controlling the freedom of admission or for shutting off the supply of steam to the radiator when heating is not required, or in case the thermostatic portion of the valve device is to be removed for repairs or cleaning, at which time the plug 22 will prevent the escape of steam from the steam main. This plug 22 may be made steam tight by suitable packing 25 and gland 24. Any other suitable means of making a steam tight joint may be employed.

In place of the static valve piece or plug 22 being arranged in alinement with the bushing 10, it may be arranged out of alinement as indicated in Fig. 4, when it is desired that the said plug shall be operated from a handle 28 and stem 27^a in a manner similar to any ordinary static valve. In the construction shown, the branch pipe 4 is provided at its top with an elbow furnishing a bearing for the vertical stem 27^a constituting the means for operating the shut-off plug

or valve 22^a, which may thus be operated by the occupant of the room to shut off the steam supply at any time desired, and thereby putting the thermostatically controlled valve devices out of controlling operation. 70

We do not restrict ourselves to any expansible medium or fluid within the chamber portion 14 and expansible or motor member 18, as it may consist of a volatile liquid or a gas or a mixture of these, and the volatile fluid thus employed may be similar to any of those now in use in thermostatic motors. 75

In practice, we prefer that the preliminary setting of the valve 11 relatively to 80 the seat 10 in assembling may be done by the screw stem 12 in the head 20 and locked by the lock-nut 20^a, while the general adjustments of the valve and seat to insure a predetermined temperature in the room may 85 be done by rotating the thermostatic motor on the threaded case 16 and securing it by the locking sleeve 17. In this way the adjustment will admit steam in volume desired, whereby it will heat such surface of 90 the radiator as will hold the room at the temperature required. For any change in the predetermined temperature to be maintained, the adjustment must be again made, setting the valve piece farther from the 95 seat for a higher temperature and vice versa. In practice, we have found that the valve will operate between "fully open" and "fully closed" positions for a change in temperature of 3 to 6 degrees Fah. and 100 hence actual regulation is automatic to prevent any material variation in the predetermined temperature to be maintained in the room because of the great sensitiveness of the thermostatic control of the valve devices between these extreme positions. 105

As will be seen, our invention comprehends the placing of the thermostatic valve operating means in a position to be acted upon by the current of cooler air flowing 110 toward the radiator and adjacent to the floor, this cooler air current on being reheated forming the means of conveying and diffusing heat throughout the room or inclosure to be warmed. The result of placing the thermostatic device in the current of cooler air flowing toward or adjacent to the lower part of the radiator is to secure as nearly as possible an average of 115 the temperature conditions of the room or inclosure, the current toward the radiation being composed of the cooler and heavier air from all parts of the room and its composition largely proportionate to the degree of lower temperature times the volume of 120 cooler spaces which are to be raised in temperature. 125

The sensitive or thermostatic device may be of any suitable length so long as it provides means of operation by an average of 130

- the air to be reheated, and we therefore do not restrict ourselves to any particular length or shape of the thermostatic devices for operating the main valve. These thermostatic devices may, moreover, be located immediately under the radiator substantially as shown, or they may be arranged adjacent to the lower portions of the radiator so long as they are arranged relatively close to the floor or wall adjacent to which the radiator may be located and be acted upon by the average cooler mixture, and we therefore do not restrict ourselves to the exact location of the thermostatic motor devices.
- 15 It will now be apparent that we have devised a novel and useful construction which embodies the features of advantage enumerated as desirable, and while we have in the present instance shown and described 20 the preferred embodiment thereof which has been found in practice to give satisfactory and reliable results, it is to be understood that we do not restrict ourselves to the details, as the same are susceptible of modification in various particulars without departing from the spirit or scope of the invention.

Having now described our invention, what we claim as new and desire to secure by Letters Patent, is:—

- 30 1. In an apparatus of the character stated, the combination of a radiator or coils, means for supplying steam thereto, a valve device for controlling the flow of steam to the 35 radiator or coils, an elongated horizontally arranged thermostatic motor device placed below the bottom of radiator or coils and along the entire length of the bottom part thereof so as to be acted upon by the air 40 passing from the room first to the thermostat and which on leaving the thermostatic motor device passes directly upward to the under part of the radiator or coils substantially throughout its entire length, and a 45 connection from the thermostatic motor for operating the valve device.

2. In an apparatus of the character stated, the combination of a radiator or coils, means for supplying steam thereto, a valve device 50 for controlling the flow of steam to the radiator or coils, and an elongated thermostatic motor device arranged immediately adjacent to the lower portion of the radiator along the length of its bottom for operating the valve device whereby it is affected by the temperature conditions of approximately all of the air which passes under the radiator and before it has risen to the radiator coils.

- 60 3. In an apparatus of the character stated, the combination of a radiator comprising a plurality of coils and having feet to hold said coils at a short distance above the floor, said coils at a short distance above the floor, with a pipe for supplying steam to the radiator, a valve to control the supply of steam

to the radiator, and an elongated horizontally arranged thermostatic motor to operate the said valve extending along substantially the whole length of the radiator and positioned under its heating coils, whereby 70 it is affected by the air passing over the floor to all of the under part of the radiator, said thermostatic motor out of contact with the radiator coils.

4. In an apparatus of the character stated, 75 the combination of a radiator comprising a plurality of coils and having feet to hold said coils at a short distance above the floor, with a pipe for supplying steam to the radiator, a valve to control the supply of 80 steam to the radiator, an elongated horizontally arranged thermostatic motor to operate the said valve extending along the length of the radiator and under its heating coils and acted upon wholly by the air before it 85 reaches the radiator coils, whereby it is affected by the air passing over the floor to the under part of the radiator, said motor comprising a fixed chamber having at one end a plurality of bellows elements having 90 their interiors in communication with the fixed chamber, an adjustable connection between the bellows elements and the valve, and a perforated case about the bellows elements and connecting the fixed chamber with 95 the valve body, and a manually controlled shut-off valve to shut off the supply of steam to the thermostatically operated valve whereby the supply of steam to the radiator may be manually controlled without interference 100 with the adjustment of the thermostatically controlled valve.

5. In an apparatus of the character stated, the combination of a radiator supported at a distance above the floor, a valve for controlling the flow of steam to the radiator arranged beyond one end of the radiator, a long thermostatic motor device arranged immediately under the radiator and extended beyond its end and secured in position, a connection between the thermostatic motor device and the valve whereby the latter is operated by variations in the air temperature immediately below the radiator, said long thermostatic motor device being 115 suspended above the floor and at a distance below the radiator and extending approximately the length of the radiator.

6. In an apparatus of the character stated, the combination of a radiator, a supply pipe 120 for admitting steam to the radiator, a valve for controlling the supply of steam passing to the radiator, and an elongated thermostatic motor device for automatically operating said valve, said elongated motor arranged below the lower portion of the radiator along the length of its bottom and comprising an elongated hollow chambered part of fixed shape, and an expansible thermostatically operated part adapted to operate 125 130

the valve and having its interior in communication with the elongated chambered part and said parts containing an expansible fluid medium, both the hollow chambered part and the expansible part being subject directly to the same heated medium.

7. In an apparatus of the character stated, the combination of a radiator or coils, a supply pipe for supplying steam to the radiator or coils, a valve for controlling the supply of steam through the supply pipe, a thermostatic motor arranged below the radiator or coils and along the length thereof and consisting of an expansible closed chambered portion one end of which is provided with

bellows members and also connected with the valve piece of the valve by a fixed casing surrounding the bellows members, and adjustable means for adjusting the bellows end of the expansible chambered portion bodily 20 to and from the valve seat whereby the valve piece may be normally adjusted relatively to the valve seat.

In testimony of which invention, we hereunto set our hands.
